UNITED STATES PATENT OFFICE

BENJAMIN A. LEGG, OF COLUMBUS, OHIO, ASSIGNOR TO THE LECHNER MANUFACTURING COMPANY, OF SAME PLACE.

DRIVE-CHAIN.

SPECIFICATION forming part of Letters Patent No. 364,117, dated May 31, 1887.

Application filed October 8, 1886. Serial No. 215,719. (No model.)

To all whom it may concern:

Be it known that I, BENJAMIN A. LEGG, a citizen of the United States, residing at Columbus, in the county of Franklin and State of Ohio, have invented certain new and useful Improvements in Drive-Chains, of which the following is a specification, reference being had therein to the accompanying drawings.

Figure 1 is an edge view of my chain, the 10 end bar of one link being placed in the clasp preparatory to closing the members of the clasp around said end bar. Fig. 2 is a similar view with one lip of the clasp bent around the end bar. Fig. 3 is a similar view with both lips 15 of the clasp bent into working position. Fig. 4 is a plan view of Fig. 3.

This chain belongs to the class which is known as "non-detachable," and is intended as an improvement upon the chain shown in 20 Patent No. 47,595 to P. Anderson, dated May 2, 1865.

In chains of the Anderson type it is necessary that the clasp or closed eye shall be of sufficient thickness at all points to withstand the 25 pull which is exerted upon it when the chain is in operation, and in practice it has been found that three serious objections are incident to the use of a clasp of this character when made of a single thickness of metal. The Anderson clasp is cast in the form of a hook, with 30 its throat open sufficiently to admit the end bar of an adjacent link, after which the eye is closed by bending. In order to facilitate the manufacture of such chains, it has been found 35 desirable to dispense with the use of cores by casting the lip of the clasp in a position at about a right angle to the plane of the side bars, and afterward bend it around the end bar of an adjacent link, such end bar serving 40 as a former or mandrel to assist in properly shaping the clasp; but in thus bending the clasp three objectionable results were produced: first, its strength was so weakened as to occasion frequent breakage; secondly, the 45 interior of the clasp would be of irregular shape, instead of being circular in cross-section, and therefore it would wear unevenly upon the end bar of the next link, and, thirdly, there would be such differences in the lengths 50 of the links as to interfere materially with properly running the chain over sprocket-wheels.

In order to obviate these objections I have made this invention, which consists, essentially, in the combination, in a drive-chain 55 link, of an end bar, a lip surrounding the end bar, and a second lip, also surrounding the end bar and overlapping the first-named lip, the lips being provided with locking devices which support the closed eye thus formed against the 60 pull of the end bar.

Having thus explained the nature of my invention, I will proceed to describe one method which I have invented for carrying it into effect.

Like letters indicate like parts in all the figures.

A A are side bars, connected at one end by end bar, B, which is circular in cross-section, and is preferably of uniform diameter throughout. At the opposite end of the link there is a clasp or closed eye consisting of two members, one of which overlaps the other. Of these members, C C' is cast in substantially U shape, as indicated in Figs. 1, 2, 3, the lip C 75 being of such length that after the end bar of an adjacent link has been seated therein it (the lip) can be bent around said end bar and be made to fit closely thereto, as indicated in Figs. 1 and 2. By reason of this member C C' being 80 comparatively thin it can be bent from the U shape into the curvilinear form around the end bar without seriously weakening it, and it can also be so bent as to fit closely said end bar, whereby the articulations of the chain can be 85 made with a high degree of perfection. In order to support this member against working strain, I combine with it a second member or lip, D, which is cast integral therewith, and after the first member has been bent around 90 the end bar, as in Fig. 2, I bend this second member or lip, D, around the first member, and by an examination of the drawings it will be seen that this lip D overlaps and rests upon and engages with the underneath lip of the 95 hook part; hence whenever in this case I use the words "overlapping lip" I refer to a lip which is bent around outside of another lip and is adapted to engage therewith and support such interposed lip against the pull of the 100 end bar. I further provide these lips with interlocking projections, preferably in the form of ribs or shoulders c d, the rib c being upon the outer face, C, the rib d being upon the in-

ner face of the lip D; but I do not wish to be limited to the precise construction and relation of parts here shown, because they might be somewhat modified without departing from 5 the spirit of my invention.

A chain thus constructed is non-detachable, it being evident that the links can only be separated after sufficiently straightening out both members of the clasp to permit the withdrawal 10 of the end bar from between them; but I have found that by the use of a sufficiently flexible and tough malleable iron a combined clasp of this sort can be opened and closed without breaking as many times as will be ordinarily 15 found necessary during the usual life of such a chain, and owing to the fact that by means of the combination of two lips forming this closed eye each lip can be made so thin that it is practicable to couple and uncouple the links 20 by the aid of such tools as are ordinarily at hand in such places where chains of this kind are commonly used.

What I claim is—

1. In a drive-chain, a closed eye consisting 25 of a lip bent into curvilinear form in cross-section, in combination with an outer overlap-

ping lip adapted to support the inner lip against the pull of the end bar, substantially as set forth.

2. In a drive-chain, a closed eye consisting 30 of a lip, C, bent into curvilinear form in cross-section, in combination with an outer overlapping lip, C', and locking devices, substantially as described, connecting the lips, substantially as described.

3. In a drive-chain, a link having two side bars connected with each other by a round end bar, and having at their opposite ends a closed eye consisting of a lip bent into curvilinear form in cross-section and provided with an 40 outer transverse rib, in combination with an overlapping lip provided with an inner transverse rib adapted to engage with the rib of the inner lip and support said inner lip against the pull of the end bar, substantially as set 45 forth.

In testimony whereof I affix my signature in presence of two witnesses.

BENJAMIN A. LEGG.
